UNITED STATES PATENT OFFICE.

CHARLES LEWIS PULLMAN, OF PEQUANAC, NEW JERSEY, ASSIGNOR TO THE PULLMAN AUTOMATIC VENTILATOR COMPANY, OF WASHINGTON, DISTRICT OF COLUMBIA, A CORPORATION OF WEST VIRGINIA.

VENTILATOR.

No. 822,074.

Specification of Letters Patent.

Patented May 29, 1906.

Application filed July 19, 1900. Serial No. 24,215.

To all whom it may concern:

Be it known that I, CHARLES LEWIS PULLMAN, a citizen of the United States, residing at Pequanac, in the county of Morris and State of New Jersey, have invented certain new and useful Improvements in Ventilators; and I do hereby declare the following to be a full, clear, and exact description of the invention, such as will enable others skilled in the art to which it appertains to make and use the same.

The object is in a simple and efficient manner to effect ventilation of a car, steamboat, or other moving object, or of the rooms of a building or other inclosed space, either by supplying air thereto or by exhausting air therefrom.

With this object in view the invention consists in the novel construction and combination of parts of a ventilating device, as will be hereinafter fully described and claimed.

In the accompanying drawings, forming a part of this specification, and in which like letters of reference indicate corresponding parts, Figure 1 is a view in perspective, exhibiting the form of device used as an intake. Fig. 2 is a view in sectional plan of the device shown in Fig. 1. Fig. 3 is a view in perspective, exhibiting the form of device used as an outtake.

Referring to the drawings, and to Figs. 1 and 2 thereof, in which a form of apparatus adapted for ventilating cars, buildings, rooms, &c., by an intake of air is exhibited, A designates a plate provided with an opening or orifice a , which has a screen a^2 . The plate may be made of one piece of metal, wood, or the like, or of a plurality of detachable sections secured together in such manner as to be adjustable lengthwise to permit the plate to be fitted to windows of different widths. Secured to the plate is a valve-casing a^3 , which may be of any suitable material and preferably in the shape shown—that is, a double inclined structure with the hip at the center of the length of the casing. Pivoted within the casing and spanning the opening a is a valve a^4 , of metal and preferably curved, and secured to the valve is a short hollow lug or projection a^5 to be engaged by the end of a two-armed lever a^6 , the arms being pivotally mounted at the hip of the casing and projecting outward through slots a^7

beyond the same. The end of the lever engaging the lug a^5 is rounded or is provided with a ball, thus effecting a ball-and-socket-joint connection between these parts, and this form of connection is that which will generally be preferred; but it is to be understood that I do not limit the invention to this particular arrangement, as any other form of joint may be employed, if preferred. Carried by the arms of the lever projecting beyond the casing is a vane a^8 , which through the medium of the joint above described will cause the valve to close that end of the casing mouthing toward the direction from which the current of air comes, so that air will be taken into the casing from the direction opposite that in which the current comes, thus at all times insuring a supply of smoke, dust, and cinder free air into the car or other space to be ventilated, while the closed end of the casing will preclude entrance of rain or snow into such space.

It will be observed that the casing a^3 is of greater length than the valve—that is to say, projects at each end some distance beyond the ends of the valve. This construction of casing is employed where the device is to be used as an air-intake, the intake resulting from the air that rushes in to fill the partial vacuum produced at the rear end of the casing by the passage of air past that end, it being apparent that by the extensions referred to the direct current or moving body of air cannot itself enter the casing, but by reason of the shape of the back of the casing will be shunted past the open end thereof, and thus create the vacuum referred to. As is well known, when a train is in motion there is always a back or resultant draft caused by the air from the rear of the train rushing in to fill the partial vacuum created by the splitting of the air by the train, and it is this back or resultant draft or current of air that is utilized in operating this device to supply air to a space to be ventilated.

The form of device shown in Fig. 3 is that which operates as an outtake and differs, essentially, from the form of device designated as the "intake," just described, in that the inclined surfaces of the casing are shortened to bring the extremities thereof nearer the line of the end walls of the orifice in the back plate, so that the end of the casing mouthing

in the direction in which the current of air is moving or in which the body may be moving will by the action of such current cause a suction that will operate to withdraw air from the interior of the space, thus effecting ventilation by an outtake of air, as opposed to the operation of the device shown in Fig. 1, which effects ventilation by an intake of air.

Having thus fully described my invention, what I claim as new, and desire to secure by Letters Patent of the United States, is—

In a ventilator, a casing, bridging an opening communicating with the chamber to be ventilated, the opposite ends of the casing being open and its outer wall being hipped to form a deflector, a curved valve pivotally

mounted within the casing, and movable automatically to cut off communication between either end of the casing and the chamber-opening, a lug secured to the outer face of the valve and having a pocket or opening, a lever pivoted to the outer wall of the casing and extending through an opening therein, one arm of the lever extending into the pocket or opening of the lug, and a vane carried by the opposite arm of said lever.

In testimony whereof I affix my signature in the presence of two subscribing witnesses.

CHARLES LEWIS PULLMAN.
